S. CURTIS SMITH, OF BOSTON, MASSACHUSETTS.

Letters Patent No. 99,117, dated January 25, 1870.

IMPROVEMENT IN SAFETY-STOP FOR WATCHES.

The Schedule referred to in these Letters Patent and making part of the same.

To all to whom these presents shall come:

Be it known that I, S. CURTIS SMITH, of Boston, in the county of Suffolk, and Commonwealth of Massachusetts, have made an invention of a new and useful Improvement in Watches, or other time-keepers; and do hereby declare the following to be a full, clear, and exact description thereof, due reference being had to the accompanying drawings, making part of this specification, and in which—

Figure 1 is a vertical section of the barrel, pillar-plate, and stop-works plate of a watch containing my invention or improvement.

Figure 2 is a horizontal section of the barrel, and of the mechanism connected therewith, which constitutes my invention.

Figure 3, an under-side view of the barrel.

Figure 4 is a view of the barrel, showing the modification of my invention.

This invention relates to means for insuring the safety of the train of a watch or time-keeper, provided with a going-barrel, whose motive-power is a coiled spring, should a fracture of such spring occur while in a contracted state.

I am aware that various devices to accomplish this purpose have been heretofore invented and patented. In all of these cases, however, a strain and concussion come upon the train, at the breaking of the spring, before such spring has time to react and recoil upon itself and upon the compensating-device, and it is at this instant of time, that the harm, if any, often occurs.

The object of this invention is to guard against harm to the train, by entirely preventing any movement of the barrel and main gear, upon fracture of the spring, and by this means, allow the spring to recoil upon itself, and spend its force in this way, which would otherwise be exerted upon the train, at the moment of breakage.

My invention consists in fixing to any convenient part of the barrel of the watch, an annular ratchet, and in pivoting to one of the plates, below the head of such barrel, in immediate proximity to the barrel, a spring-pawl or click, this pawl taking into the teeth of the ratchet, and permitting it to travel but in one direction only, and that, the one affected by the power of the main-spring.

In the drawings accompanying this specification, and which illustrate my invention—

A denotes the pillar-plate, and b, the stop-works plate of a watch containing a "going-barrel," this barrel being shown at c, and its main gear-wheel at d,

these parts being arranged in manner similar to ordinary watches of its class.

In carrying out my invention, I affix to the under or outer face of the barrel-head, and immediately below the main gear, an annular ratchet, e, while, to the pillar-plate of the watch, I pivot a spring-pawl, f, in such manner that it shall take into the teeth of the ratchet, as represented in fig. 1 of the drawings.

It will, of course, be at once apparent that the adoption of this ratchet and pawl permit of rotation of the barrel but in one direction, this direction, as before observed, being that in which it is forced to travel by the distension of the main-spring.

Should a fracture of the main-spring take place, the spring-pawl acts to instantly arrest any movement of the barrel in a reverse direction; consequently the force of the recoil of the spring is spent upon itself, and the entire immunity of the main or other gears of the train from its action, is secured, whereas, in other devices, before the inertia, consequent upon the recoil of the spring, can be changed from itself to the barrel, it is spent for an instant upon the train.

This ratchet and pawl occupies no valuable space in a watch-movement, while its extreme simplicity and efficiency will at once recommend it to watch-makers, to whom this specification is chiefly addressed.

I do not confine myself to the locality of the ratchet, as herein illustrated, as it will be evident that this locality may be varied, without violating the spirit of my invention, which is intended to embrace the application, to the barrel and plate of a watch, of an annular ratchet and a stop-pawl, in such manner as to operate as before explained.

The ratchets, for instance, may be applied to the under side or face of the barrel-head, as shown in fig. 4 of the drawings, the spring-pawl being pivoted to the pillar-plate and below the barrel.

What I claim, and desire to secure by Letters Patent, is—

The combination, with the "going"-barrel of a watch or other time-piece, of an annular ratchet fixed to or moving in unison with said barrel, and a spring-pawl attached to the pillar-plate, and operating in connection with said ratchet, substantially as and for the purposes shown and described.

S. CURTIS SMITH.
